UNITED STATES PATENT OFFICE.

EDGAR M. GRUEN, OF NEW YORK, N. Y.

CLASP FOR SANITARY BELTS.

Application filed September 15, 1923. Serial No. 662,901.

To all whom it may concern:

Be it known that I, EDGAR M. GRUEN, a citizen of the United States, and resident of the borough of the Bronx, in the county 5 of Bronx, city and State of New York, have invented certain new and useful Improvements in Clasps for Sanitary Belts, of which the following is a specification.

The main object of this invention is to 10 provide an effective clasp of simple construction readily operable to clasp the reduced end of a sanitary pad or napkin.

A further object of the invention is to 15 provide a clasp that may be quickly operated to release the pad by an outward pull on the end of the pad.

A clasp constructed in accordance with 20 this invention while especially adapted for the use herein indicated, may be used for many purposes, for instance, as a garment supporter and for other like uses.

The invention is designed particularly for use with the well known Kotex pads, but of course, it is capable of use with any 25 form of pad or napkin having soft or reduced ends adapted to be grasped firmly between the clasp members.

In the drawing:

Fig. 1 is a front view of the device showing one end of a pad secured thereto;

Fig. 2, a vertical longitudinal sectional view taken on the line 2—2 of Fig. 1;

Fig. 3 a perspective view of the clasp open and detached from the holding belt;

Fig. 4 a view similar to Fig. 3 showing clasp in closed or gripping position;

Fig. 5 a vertical longitudinal sectional view of the clasp in open or released position, and taken approximately on the line 40 5—5 of Fig. 3;

Fig. 6 a vertical sectional view similar to Fig. 2, showing the manner of releasing the clasp by an outward pull on the ends of the clasped fabric element;

Fig. 7 a transverse sectional view taken on the line 7—7 of Fig. 2;

Fig. 8 a transverse sectional view taken on the line 8—8 of Fig. 6; and

Fig. 9 a transverse sectional view taken 50 on the line 9—9 of Fig. 6.

Referring to the various parts by numerals, 1 designates the lower portion of a belt of any desired form. To this belt is secured a depending fabric tape 2 to the lower end of which the clasp is connected. The clasp consists of a body part 3 and a

tubular clamping slide 4 mounted on the body part and arranged to move longitudinally up and down thereon.

The body part of the clasp is formed of a comparatively narrow plate of sheet metal having a slot 5 near its upper end to receive the tape 2, said slot having a lower contracted part 6 adapted to receive a locking tongue formed on the upper end of the clamping slide, as will be described hereinafter. A suitable distance from its lower or free end the plate 3 is formed with a mouth 7 which is in the form of a transverse slot extending inwardly and transversely of the plate 3 from the left hand edge, as shown clearly in Fig. 3. This slot separates the clasp head 8 from the body of the plate, said head being connected to the plate 3 by a resilient neck 9 at the right hand edge of the plate, the inner edge of said neck forming the inner wall of the mouth 7. One of the functions of this resilient neck is to permit the head to yield or flex laterally when the clamping slide is forced into or out of clamping position, as will be described. A portion of the plate 3, along the upper margin of the mouth 7 is bent forwardly to form a stop flange 10, said flange extending transversely of the plate 3. This flange is cut away and rounded at its outer or left hand corner 11 to permit the clamping slide to swing laterally with the head 8. The side edges of the head are formed with forwardly extending longitudinal flanges 12 and 13. The flange 13 extends along the outer or right hand edge of the neck 9 to strengthen the neck and prevent it being bent or deformed either forward or rearward. These flanges 90 form a channel in which the material to be clamped may be conveniently arranged and also serve as guides for the clamping slide. The upper edge of the head 8, which forms the lower margin of the mouth 7, is serrated or toothed, as shown, to securely hold the fabric clamped over the head. The head 8 is dished or bulged forwardly between the flanges 12 and 13 to form the hollow or concave back part 14 and the convex forward side 15, said parts being curved both longitudinally as well as transversely of the head. The convex forward side of the head is formed with transversely extending serrations in the form of sharp teeth 16 into which the fabric is forced by the clamping slide. It will be noted that the teeth 110

16 do not project beyond the outer longitudinal edges of the flanges 12 and 13. The upper rigid part of the plate 3 close to the stop flange 10 is formed with a forwardly 5 projecting transverse locking ridge 17. This ridge is formed by pressing the metal of the plate 3 forwardly so that the ridge and the flange 10 form a transverse channel 18 in which the locking tongue of the clamp- 10 ing slide will rest when the slide is in clamp- ing position.

The clamping slide is open ended and tubular and slides readily longitudinally of the plate 3 and over the flanges 12 and 13. 15 It is of sufficient length to substantially enclose said flanges and the head 8. The upper edge of the forward wall of the slide is provided with an upwardly extending locking tongue 19 whose free end is bent 20 inwardly to engage and ride on the forward face of the plate 3 above the mouth 7. The locking tongue 19 is adapted to enter the part 6 of the slot 5 to hold the slide in its released position, as shown in Figs. 3 and 5. 25 The tongue 19 is formed with a small upwardly extending lug 20 which acts as a catch to hold the locking tongue in the slot, said lug being adapted to be forced inwardly beyond the lower edge of the fabric tape 30 2. The fabric of the tape will yield sufficiently to permit the lug to be forced into and out of locking position.

The operation of the device is as follows:

35 The clamping slide is first moved up to the position shown in Figs. 3 and 5. The soft reduced end of the pad or napkin is passed into the mouth 7 and then folded forwardly down over the convex side of the head 8 between the flanges 12 and 13. The slide is then forced down over the folded fabric and over the flanges 12 and 13 thereby forcing the fabric into close contact with the teeth 16 and into hollow part 14. As 40 the locking tongue 19 rides up over the locking ridge 17 the slide will move forwardly and as the upper edge of the slide is below the flange 10, the forward thrust on the slide due to the tongue riding up the cam- 45 like ridge 17, will result in a forward twisting of the head 8 until the tongue 19 snaps over the locking ridge into the channel 18. When the tongue is in the said channel the head will spring back to its normal position. 50 Fig. 7 shows the transverse positions of the head 8 and the slide when the tongue 19 is in the channel 18. Figs. 8 and 9 show the twisting action of the slide and the head when the tongue is riding over the peak of 55 the ridge 17. The clamping slide will be first forced forwardly and that portion enclosing the shorter flange 12 and the entrance to the mouth 7 will be free to move until the rear wall of the slide engages the 60 rear wall of the head if the fabric clamped 65

will compress sufficiently to permit such movement, and then the forward edge of the flange 13 will be in engagement with the forward wall of the slide, as shown in Fig. 8. As the tongue 19 is forced over the ridge 17 the head will be slightly twisted about the neck 9. The stop flange 10, when engaged by the tongue 19, limits the downward or clamping movement of the slide 4.

The Kotex pad or other fabric article 75 is released from the clasp by moving the clamping slide up on the plate 3. This may be done readily by pulling outwardly on the ends of the fabric, as illustrated in Fig. 6. The outward pull of the fabric results 80 in an upward thrust on the slide 4. The upward movement of the slide causes the tongue 19 to ride over the locking ridge 17 and the slide and the head 8 will be twisted laterally precisely as when forcing 85 the slide into clamping position. Figs. 6, 8 and 9 illustrate the lateral twisting of the slide and the head during the movement of the tongue 19 over the ridge 17 both in the clamping and in the releasing movement of 90 the slide.

When the slide is in its released position with the tongue 19 in the part 6 of slot 5, the lower edge of the slide will rest on the stop flange, as shown in Fig. 5.

What I claim is:

1. A clasp comprising a body part formed with a head at its lower end and connected to the body part by a narrow neck, a laterally extending open mouth being formed between the head and the main body of the clasp, a transverse stop flange formed on the body part along the upper transverse margin of the said mouth, a transverse locking ridge formed in the body part above the stop flange whereby a transverse channel will be formed between the stop flange and the locking ridge, and a clamping slide mounted to move longitudinally on the body part and formed with a locking tongue 100 adapted to ride over the locking ridge and to rest in the channel between the locking ridge and the stop flange when the slide is 105 in its clamping position.

2. A clasp comprising a body part formed with a head at its lower end and connected to the body part by a narrow resilient neck, a laterally extending open mouth being formed between the head and the main body of the clasp, a transverse stop flange 110 formed on the body part along the upper transverse margin of the said mouth, a transverse locking ridge formed in the body part above the stop flange whereby a transverse channel will be formed between the stop flange and the locking ridge, and a clamping slide mounted to move longitudinally on the body part and formed with a locking tongue adapted to ride over the locking ridge and to rest in the channel be- 115 120 125 130

tween the locking ridge and the stop flange when the slide is in its clamping position, the resilient neck permitting the head to be flexed or twisted laterally by the slide 5 when the locking tongue rides over the locking ridge.

3. A clasp comprising a body part formed with a head at its lower end and connected to the body part by a narrow neck, a laterally extending open mouth being formed between the head and the main body of the clasp, a transverse stop flange formed on the body part along the upper transverse margin of the said mouth, a transverse locking ridge formed in the body part above the stop flange whereby a transverse channel will be formed between the stop flange and the locking ridge, flanges extending along the longitudinal edges of the head, a clamping slide mounted to move longitudinally on the body part and adapted to slide to its clamping position over the head and the flanges thereon, and a locking tongue formed on the upper end of the slide and adapted to ride over the locking ridge and to rest in the channel between the locking ridge and the stop flange when the slide is in its clamping position.

4. A clasp comprising a body part formed with a head at its lower end and connected to the body part by a narrow resilient neck, a laterally extending open mouth being formed between the head and the main body part of the clasp, a transverse stop flange formed on the body part along the upper transverse margin of the said mouth, a transverse locking ridge formed in the body part above the stop flange whereby a transverse channel will be formed between the stop flange and the locking ridge, flanges extending along the longitudinal edges of the head, a clamping slide mounted to move longitudinally on the body part and adapted to slide to its clamping position over the head and the flanges thereon, and a locking tongue formed on the upper end of the slide and adapted to ride over the locking ridge and to rest in the channel between the locking ridge and the stop flange when the slide is in its clamping position, the resilient neck permitting the head to be flexed or twisted laterally by the slide when the locking tongue rides over the locking ridge.

5. A clasp comprising a body part formed with a head at its lower end and connected to the body part by a narrow neck, a laterally extending open mouth being formed between the head and the main body of the clasp, a locking ridge formed in the body part above the open mouth, a clamping slide mounted to move longitudinally on the body part and adapted to enclose the head and the mouth when in its clamping position, a locking tongue formed on said slide and adapted to ride over the locking ridge, and a stop

for limiting the movement of the clamping slide to its clamping position after the locking tongue is moved over the locking ridge.

6. A clasp comprising a body part formed with a head at its lower end and connected to the body part by a narrow resilient neck, said head being bulged forward to form a convex gripping surface and a concave back, a laterally extending open mouth being formed between the head and the main body part of the clasp, a transverse stop flange formed on the body part along the upper transverse margin of the said mouth, a transverse locking ridge formed in the body part above the stop flange whereby a transverse channel will be formed between the stop flange and the locking ridge, forwardly extending flanges extending along the longitudinal edges of the head, a clamping slide mounted to move longitudinally on the body part and adapted to slide to its clamping position over the head and the flanges thereon, and a locking tongue formed on the upper end of the slide and adapted to ride over the locking ridge and to rest in the channel between the locking ridge and the stop flange when the slide is in its clamping position, the resilient neck permitting the head to be flexed or twisted laterally by the slide when the locking tongue rides over the locking ridge, and one of said flanges engaging the forward wall of the slide when the tongue is forced over the locking ridge.

7. A clasp comprising a body part formed with a head at its lower end and connected to the body part by a narrow neck, a laterally extending open mouth being formed between the head and the main body of the clasp, a transverse stop flange formed on the body part along the upper transverse margin of the said mouth, a transverse locking ridge formed in the body part above the stop flange whereby a transverse channel will be formed between the stop flange and the locking ridge, and a clamping slide mounted to move longitudinally on the body part and formed with a locking tongue adapted to ride over the locking ridge and to rest in the channel between the locking ridge and the stop flange when the slide is in its clamping position, the body part being formed with a slot near its upper end to receive the locking tongue when the clamping slide is in its released position.

8. A clasp comprising a body part formed with a head at its lower end and connected to the body part by a narrow neck, a laterally extending open mouth being formed between the head and the main body of the clasp, a transverse stop flange formed on the body part along the upper transverse margin of the said mouth, a transverse locking ridge formed in the body part above the stop flange whereby a transverse channel will be formed between the stop flange and

the locking ridge, a clamping slide mounted to move longitudinally on the body part and formed with a locking tongue adapted to ride over the locking ridge and to rest in the channel between the locking ridge and the stop flange when the slide is in its clamping position, the body part being formed with a slot near its upper end to receive the locking tongue when the clamping slide is in its released position, and a latch lug formed on the locking tongue and adapted to hold said tongue in said slot.

9. A clasp comprising a body part formed with a head at its lower end and connected to the body part by a narrow neck, a laterally extending open mouth being formed between the head and the main body of the clasp, a stop flange formed on the body part at the upper transverse margin of the said mouth, a locking ridge formed on the body part and spaced above the stop flange, and a clamping slide mounted to move longitudinally on the body part and formed with a locking tongue adapted to ride over the locking ridge and snap into place between the said ridge and the stop flange in the closed position of the clamping slide.

10. A clasp comprising a flat sheet metal body part formed with a head at its lower end and connected to the body part by a narrow neck, a laterally extending open mouth being formed between the head and the main body of the clasp, a locking ridge formed on the body part above the open mouth, a flat tubular clamping slide mounted to move longitudinally on the body part and adapted to enclose the head when in its

clamping position, a locking tongue formed on said slide and adapted to ride over the locking ridge, and a stop for limiting the movement of the clamping slide to its clamping position after the locking tongue is moved over the locking ridge.

11. A clasp comprising a flat sheet metal body part having substantially straight parallel side edges and formed with a head at its lower end, said head being connected to the body part by a narrow neck, a laterally extending open mouth being formed between the head and the main body part, a flat tubular clamping slide mounted to move longitudinally on the body part and adapted to enclose the head when in clamping position, and means for limiting the downward movement of the clamping slide to clamping position.

12. A clasp comprising a flat sheet metal body part having substantially straight parallel side edges and formed with a head at its lower end, said head being connected to the body part by a narrow neck, a laterally extending open mouth being formed between the head and the main body part, a flat tubular clamping slide mounted to move longitudinally on the body part and adapted to enclose the head when in clamping position, means for limiting the downward movement of the clamping slide to clamping position, and means to yieldingly lock the slide in its clamping position.

In testimony whereof I hereunto affix my signature.

EDGAR M. GRUEN.
